UNITED STATES PATENT OFFICE

WALTER GUY FRAZEE, OF CEDAR RAPIDS, IOWA, ASSIGNOR TO IOWA MANUFACTURING COMPANY, OF CEDAR RAPIDS, IOWA, A CORPORATION OF IOWA

APPARATUS FOR MIXING MATERIAL FOR MAKING ROADS

Application filed September 25, 1929. Serial No. 395,026.

My invention relates to an apparatus designed to be employed in connection with the construction of highways for forming a cementitious mixture of gravel or crushed stone and an asphaltic binder of the kind usually termed road oil, which is relatively heavy and viscous at ordinary atmospheric temperatures, but thin and free flowing when heated. In the construction of such gravel or crushed stone roads surfaced with a cemented mixture of the gravel and road oil, it is common practice to spray the oil in heated and fluid condition upon the top of the gravel, and then plow the surface to mix the oil and gravel, the spraying and plowing being frequently repeated, and the surface finally rolled to compact it. This procedure is entirely impossible throughout the winter season in the cooler climate, and even in the summer time, if the gravel is at all damp good results are impossible. Furthermore, even under the most favorable atmospheric and climatic conditions the heated oil cools more or less irregularly while being applied, so that uniformly good results cannot be obtained. The object of my invention is the provision of an efficient apparatus which shall be free from the objections incident to the prior practice mentioned, and which to that end, shall employ means for drying and heating the gravel and mixing it with the proper amount of heated oil at or near the section of the road being surfaced, continuously and in manner and quantity sufficient to be applied in mixed and heated condition to the roadway, and which can readily be moved as the work of road making progresses to enable the construction of the road to be carried on conveniently and rapidly, and under relatively unfavorable climatic conditions.

In carrying out this main purpose and object, I have devised and invented the road material mixing apparatus illustrated in the accompanying drawings and hereinafter described in detail and embodying various novel features in the combination and arrangement of parts of the apparatus in cooperative relation to effect the results and accomplish the ends in view; in the pro-

vision of means for causing a substantially continuous and regulated flow of raw materials through the drying and heating and mixing devices to the mixed material compartment of the apparatus; in the arrangement of the frame work and various portions of the apparatus in separable parts and units to permit convenient transportation of the apparatus; and in various improvements and novel details of construction relating to certain portions of the apparatus, as the drying drum, gravel and oil feeding means, hoisting devices, etc., incidental to the features of construction before mentioned.

In the appended claims the essential elements of my invention are more particularly pointed out, it being understood, however, that my invention is susceptible of variation and modification in the construction and arrangement of various parts, and by the substitution of equivalent means and mechanism for those particularly described, and I therefore intend that my claims shall be construed to include all such modifications and equivalent elements, so far as they fall within the true spirit and scope of my invention and are not found in the prior art.

Of the drawings which illustrate a road material mixing apparatus embodying my invention in a desirable and preferred form;

Figure 1 is an elevation of what will be termed the right side of the apparatus, set up and connected for use;

Fig. 2 is a plan view of the same;

Fig. 3 is an end view of the apparatus looking from what will arbitrarily be termed the "rear" end of the apparatus towards the front end;

Fig. 4 is a vertical section of the heating drum in a plane extending axially of the same;

Figs. 5 and 6 are cross-sections of the same on planes indicated respectively by the dotted lines 5—5 and 6—6, viewed in the direction indicated by the arrows;

Fig. 7 is a view looking from rear to front of the end of the combustion chamber casing and the discharge chute of the drying drum;

Fig. 8 is a side view of a reciprocating feeder for regulating the passage of gravel

(or like material) from the supply bin to the drying drum;

Fig. 9 is a somewhat diagrammatic view of the oil passages, and a heating coil for heating the road oil provided with by-pass valves for shutting off sections of the coil at will;

Fig. 10 is a vertical section of a pug mill, showing also certain mechanisms regulating the supply of materials to it;

Fig. 11 is an end view of the reciprocating feeder illustrated in Fig. 8;

Fig. 11^a is a detail of construction of the feeder supporting frame;

Fig. 12 is a view of one of four similar ratchet mechanisms used for raising and lowering the two compartment bin structures used to contain the raw gravel and mixed materials;

Fig. 13 is a transverse section of the elevator casing on the dotted line 13—13 of Fig. 1;

Fig. 14 is an elevation of the left side of the heating drum and a supporting truck and other parts of the apparatus carried by said truck;

Fig. 15 is an elevation of the parts shown in Fig. 12 viewed at right angles to the position shown in such figure;

Fig. 16 is a detail showing in top plan view certain slide members or shoes used for connecting one of the corner posts and the adjacent corner of the bin structure;

Fig. 17 is a detail showing in side elevation certain adjusting mechanism at the lower end of the chain of elevator buckets;

Fig. 18 is a vertical section, in a plane extending longitudinally of the machine, of a measuring device for delivering heated gravel to the pug mill;

Fig. 19 is a view, looking towards the left side of the machine, of the automatic weight-controlled mechanism for governing the action of the gravel-measuring device and the oil measuring device for delivering charges of gravel and oil into the pug mill, parts of the gravel measuring device in front of said weight-controlled mechanism being broken away to enable it to be shown;

Fig. 20 is a front elevation of the upper end of the gravel elevator and gravel-measuring and oil-measuring devices and associated mechanism at the right end of the pug mill; and

Fig. 21 is a horizontal section of the oil-measuring device in a plane extending axially of the same.

Like reference characters indicate like parts in all the figures of the drawings.

Before entering upon a detailed description of the construction of the apparatus, its general organization may first be briefly explained. The apparatus, or material mixing plant includes a framework of knock-down construction made up of corner columns or posts and bracing and connecting members

which may be erected and taken down, and which when erected is arranged to support a two-compartment bin structure, one compartment, with which is associated a separable feeding device, for holding the supply of cold raw gravel (or like granular material consisting wholly or largely of small fragments of stone-like character), and the other compartment for receiving the heated material mixed with road oil. This framework is arranged to also support a frame unit consisting of a platform upon which is mounted a pug-mill used for mixing the gravel and road oil and the motor for operating the pug-mill together with gravel and oil metering or measuring devices and certain registering instruments associated with the pug-mill and certain connecting parts and members. The bin structure forms one separable unit which in the completed structure ready for operation is secured to the corner columns, and the pug-mill platform and parts carried by it form a second separable unit, also secured to the corner supports, and both units are so constructed that they may be loaded together on a truck for transportation when the apparatus is to be moved to a different location.

The remaining portions of the apparatus are in the present instance all carried by a separate single truck by which they may be transported from one location to another. These portions include a rotary drying and heating cylinder or drum arranged to receive the raw gravel, a burner for heating the drum, an elevator for transferring the dried and heated gravel to the pug-mill on the framework before mentioned, a pump arranged to be connected with a supply of road oil and operating to force the oil through a heating coil associated with the heating drum before mentioned and through a metering device which delivers it to the pug-mill, and a motor and connections for rotating the heating drum and actuating the feeding device associated with the raw material bin, as well as the other devices mounted on said truck.

Describing now in detail the specific construction of the apparatus as illustrated, the two corner posts or columns 1—1 on the right side of the frame are rigidly connected together in the assembled apparatus by a pair of detachable diagonal brace bars 2—2 which at their upper ends are bolted to a connecting plate 3 and at their lower ends are bolted to said corner posts. The other two corner posts 4—4 at the left side, are similarly connected together by diagonal bars marked 2^a and all four of the corner posts, which are formed of I-beam structural iron, are equipped each at their lower end with a supporting base structure 7 of suitable construction to provide adequate support on the ground.

The upper portions of the posts are con-

5 nected together by the separable platform unit which includes a pair of beams 6—6^a extending from front to rear of the apparatus and a pair of cross beams 7—7^a resting upon and secured to the beams 6 and 6^a, the beams 6—6^a intersecting the beams 7—7^a near their opposite ends in such manner that the posts 1 and 4 of the framework when erected will lie adjacent the outer ends of such beams 10 in the four outer angles which the beams make with each other at the corners of the frame. The beams 7—7^a are also connected by frame bars 8, 9, 10, 11, 12 and 13, to provide a platform frame to which are rigidly secured grating sections marked 14, 15, 16, 17 and 18 which 15 form a walkway. Around the outside of the group of gratings forming the walkway is arranged a railing which may be constructed of supporting members 19 and railing members 20, 20^a secured to the platform frame and arranged as illustrated or in any other suitable manner.

20 For the purpose of affording access to the pug-mill and other parts of the machine reached by the walkway above mentioned, I have provided a stairway marked 21 as a whole, extending from the ground to the platform frame and arranged to land adjacent the grating sections 16 and 18 at the left hand 25 front portion of the framework.

25 The two-compartment bin unit for holding the raw gravel and the heated treated mixture is a rectangular structure which includes four vertical leg members 22 at its corners which may conveniently be formed of angle iron, and connecting frame members 23 to which are riveted sheet metal plates 24 forming the upper walls of the bins and a cross 30 partition 25 separating the bins. The four inclined and converging bottom walls 26 of each bin are similarly constructed of sheet metal walls riveted to suitable frame members and terminate in discharge openings at the bottom.

35 40 The two legs members 22 of the bin unit at each side of the machine are connected near their bottom ends by a cross bar 27, and the legs and frame work preferably are braced by diagonal and vertical bracing members, all marked 28, directly riveted together, or connected through connecting plates, as the plates marked 29.

45 At the four corners of the bin structure the angle-iron leg members 22 are equipped with 50 pairs of shoes or slides 30—30^a adjacent their top and bottom ends which extend over the flanges of the leg columns and serve as guides in raising and lowering the bins when setting up the apparatus. Each slide 30 extends over the portion of the flange on one side of the 55 particular I-beam extending from the central web in one direction and the corresponding slide 30^a extends over the opposite portion of said flange.

60 65 Both the pug-mill platform and the bins,

temporarily bolted together for the purpose, are raised and lowered upon the corner columns by means of a special hoisting mechanism which I have devised for the purpose, the actuating parts of one member of which are shown in detail in Fig. 12. This apparatus (see Figs. 12, 15, 18 and 19) includes four cables 31 arranged to run over winding drum 32 severally rotatably mounted in bearings carried by the supporting bases 7 of the four corner posts, and each engaging in turn a sheave 33 rotatably mounted in a bracket 34 at the top of the particular corner post, a sheave 35 carried by the base of the pug-mill platform, and a sheave 33^a which is mounted on the same pivot pin as the sheave 33, the ends of the cable being anchored to the corner post adjacent the sheave 35.

70 75 As shown in Figs. 12 and 15, each winding drum 32 is associated with a ratchet wheel 36 which is fixed to the short shaft, marked 37 to which the drum 32 is itself secured. This shaft 37 may conveniently be mounted, as shown, in a pair of bracket plates 38 riveted severally to the vertical flanges of a pair 80 of blocks 39 which are L-shaped in cross-section and which are riveted to the opposite flanges of the corner posts. A foot plate 40 is secured to the lower and horizontally disposed flanges of the blocks 39 to provide adequate support upon the ground for the corner posts of the framework.

85 90 The detent 41 of the ratchet mechanism forms part of a foot treadle 410 which is pivoted in a bearing block 42 secured to the horizontal lower flange of one of the blocks 39, and is yieldingly stressed into engagement with the ratchet wheel 36 by a coiled compression spring 43. The pawl 44 of the mechanism is pivoted to a rocking actuating lever 45 which itself is pivotally mounted in the bearing block 42 before mentioned and is formed with an extension 450 below the pivot forming a blocking member. As shown, the pawl 44 is formed with a tail 440 which at times cooperates with the lower end of a spring-pressed trigger 46 slidably mounted in the body member 45 of the actuating lever. This trigger is formed with a right angled bend at its upper end which may be latched in a notch 451 in the upper end of the body member 45 to hold the trigger in inoperative position with its spring under compression. The operating handle (marked 45^a) of the lever 45 is preferably made detachable, and 100 105 may conveniently consist, as shown, of a straight handle member arranged to fit in a socket formed in the body of the lever.

110 115 It will be understood that in hoisting the bins and pug-mill platform the operating lever is lifted to rotate the winding drum, the detent yielding to the sloping faces of the ratchet teeth and automatically making spring-pressed engagement to permit the lever to be lowered and again raised in the 120 125 130

usual manner. When lowering the bins and platform (assuming the parts to be in the position shown in Fig. 12), the foot treadle is first depressed and held down to disengage 5 the detent 41, and the handle then lowered under the load of the parts connected to the cable, in the course of which movement the pawl 44 will assume a more nearly horizontal position, and its tail portion 440 will contact 10 with the trigger 46 and shift it, compressing its spring. The foot lever is then released to permit the detent 41 to engage a ratchet tooth, and as soon as the stress on the pawl 44 is relieved the spring-pressed trigger 46 15 will snap it out of engagement with the tooth of the ratchet wheel, when the operating handle may be lifted to make a new engagement between the pawl and ratchet wheel, and the operation repeated.

20 It may here be explained that in setting up the apparatus the corner posts or columns are connected separately to the four corners of the bin by means of the slides 30—30^a before mentioned, while the bin and pug-mill 25 platform (which at the time are temporarily bolted together at each corner) in the lowered position required for transportation, and the platform (carrying with it the bin structure), is then hoisted to a position in 30 which the bin structure will stand at its proper level and the bin legs then securely bolted to the corner posts or columns. To 35 secure adequate strength and rigidity the corner legs of the bins are in the present instance bolted to the corner post at their top and bottom, and also at an intermediate point. The braces 2—2 and 2^a—2^a are then bolted to the corner posts and to the cross-bars 27 of the bin frame to further secure 40 rigidity, and the pug-mill frame is then unbolted from the bins and raised further to its proper position and bolted to the corner posts.

Passage of material through the discharge 45 opening at the bottom of the bin (marked A) for containing the cold raw gravel is controlled by a feeding mechanism which may be adjusted to deliver a regulated supply of material to the heating drum later to be described. This mechanism (see Figs. 1, 8 and 11) is detachable from the bin structure 50 for purposes of transportation, and consists of a detachable framework, marked 50 as a whole, suitably constructed to be bolted to 55 the framework of the bin unit above described, in which is mounted a reciprocating feeding mechanism having a variable throw. The feeder frame includes a pair of beams 501—502 arranged to be bolted at their right 60 ends to the cross-bar 27 of the bin frame, and at their opposite ends arranged to be similarly bolted to a cross-bar 503 secured to the lower ends of vertical bars 503^a secured to the bin frame. To the beam 501 is secured 65 a pair of vertical frame members 501^a—501^a,

and to the beam 502 is secured a pair of similar members 504, 504 the members 501^a and 504 being connected by other frame members 505 running from front to rear and cross-members 505^a to form a skeleton box structure. 70

Within the skeleton box structure and stationarily supported by pairs of vertical bracket members 51—51 secured to the opposite frame bars 505—505, (see Fig. 8) is a 75 feeder box having a front wall 506, side walls 507, a collar 508 surrounding the neck 509 at the bottom of the hopper, and a top wall 510 to the rear of the collar 508,—see Figs. 8 and 11. The rear end of the feeder box is 80 open and immediately below the plane of the lower edges of the side walls and front wall is arranged a reciprocating feeder plate 54 formed with opposite side flanges 540 which extend upwardly along the side walls 85 of the feeder box. Immediately below the plane of the bottom of the collar 508 and also of the neck of the hopper, is arranged a sliding gate 511 which may be manually operated in any suitable manner, as by means 90 of a handlever 512.

The feeder plate 54 before mentioned is supported by pairs of opposite rollers 55 journaled in the lower feeder frame members 505, and is reciprocated by a rocking frame consisting of a rock shaft 58 to which is secured a central vertical rock arm 56 equipped with a roller arranged to work between a pair of blocks secured to the under side of the plate 54 centrally thereof, and including a horizontal arm 57 secured to said shaft at one side of the frame, this arm preferably being telescopic in construction, as shown,—for the purpose of adjusting its length. The shaft 58 of the rocking frame 100 is pivoted in bearings 59 carried by opposite bearing brackets 59^a secured to the lower members 505 of the feeder frame.

The discharge opening at the bottom of the bin (marked B) for containing the heated 105 mixed material is arranged to be opened and closed by means of a manually operated gate or slide 60, (see Fig. 3).

The pug-mill which forms a part of my material-mixing apparatus may be of any 110 suitable design, the general construction employed by me being illustrated in Figs. 2 and 10, from which it will be noted that the mill includes a casing 61 mounted upon base members 62 and having end walls in which is rotatably mounted the shaft 63 to which sectional hub sections carrying spaced blades 64 are secured to form a strong and rugged mixing and stirring member. The motor 65 for driving the pug-mill and the clutch 66, both 115 of which are shown diagrammatically, may be of any suitable construction adapted to perform the well understood functions of such devices, numerous commercial forms 120 being well known. A worm-driven reducing 125

gear device 67 connected to the driven clutch member of the clutch 66 is also shown diagrammatically, and as the purpose and construction of such devices are well known no detailed description is considered necessary. To the end of the shaft carrying the worm wheel of the reducing gear is fixed a sprocket wheel 68, connected by a sprocket chain 69 with a sprocket wheel 70 fixed to the end 10 of the shaft 63 of the pug-mill. A gravel measuring device for delivering measured charges of heated gravel to the pug-mill, and a metering device for simultaneously delivering measured charges of heated road oil to 15 said mill, both mounted on the pug-mill platform, will be described at a later point.

Turning now to a description of the parts permanently mounted upon a truck for transportation, (see Figs. 1, 2, 3 and 14) the frame 20 of the truck is, in the assembled apparatus when ready for operation, arranged at the right side, immediately to the rear of the raw material bin A. The longitudinal side beams or sills 71 of the truck frames are connected by angle plates, or otherwise, with cross beams 72, 72^a, 72^b, 73, 74, 75, 76, 77, 78 and 79 to form a rigid frame which is supported on the front wheels 80—80 and rear wheels 81—81, the non-rotatable axle of the front 25 wheels being pivoted to rock upon a bolster block 82 in order that the wheels may adjust themselves to irregularity in the surface of the ground.

The drying and heating cylinder or drum 30 is equipped near its rear end with a bearing ring 84, and at a point between its center and front end with a similar bearing ring 85, through which it is rotatably supported upon a pair of front bearing rollers 86, and a pair 35 of rear bearing rollers 87. The front rollers are flanged at their rear sides and are journaled in bearings carried by the cross-beams 72^a—72^b, and the rear rollers are flanged on the front sides and are carried by the cross 40 beams 75—76 (see Figs. 1, 4 and 14). It will be understood that the two rollers 86 are arranged to engage the ring 85 on opposite sides of the vertical axial plane of the cylinder, and that the rollers 87 are similarly arranged. 45 The flanges of the rollers 86 and 87 serve to prevent longitudinal displacement of the heating drum, but to relieve the rearward strain upon the roller 86 I have provided a thrust bearing arranged vertically beneath 50 the axis of the drum.

As illustrated (see Fig. 4) this thrust bearing comprises a roller 88 rotatably mounted on an approximately vertical axis in a block 55 which is adjustable in a forward and rearward direction on a seat formed by the top faces of the cross-beams 72^a—72^b, by means of an adjusting bolt 90 engaging a threaded seat in a lug formed on the lower side of the block 89 between the two cross-beams.

At its front end the heating cylinder or

drum is surrounded by a stationary hood 91, the annular front wall 92 of which makes sealed connection with the cylinder between the outwardly projecting flanges of two sectional rings 94—94^a which are clamped tightly to the drum against an interposed asbestos gasket 93 by means of clamping lugs at the meeting ends of the sections of the rings. It will be noted that the distance between the sealing rings 94 and the front thrust roller 88 is small, which has the advantage of minimizing trouble which might arise from expansion of the drying drum.

To the top portion of this head is secured the base portion 105 of the smoke stack 106, which is hinged to the base portion, so that it may be turned to a horizontal position for transportation, as indicated by dotted lines in Fig. 1. At the bottom of the front wall of the hood and opening into a downwardly offset portion thereof, I have provided a hinged door 91^b (see Figs. 4 to 11) to enable the dirt and soot which may collect in the hood to be cleaned out.

To the rear wall 95 of the hood 91 is secured a hopper 96 extending under the discharge end of the feed box and feeder plate 54 of the gravel feeding mechanism before described, see Figs. 4 and 8, and at the entrance of the hopper casing into the hood the opening is automatically variably opened and closed by a swinging gate or valve 97 which permits the stream of gravel to pass under it while closing the opening thereabove so as to prevent escape of the heated gases from the cylinder and maintain a good draft in the flue. The lower end of the hopper extends into a large central opening in the annular front wall 98 of the drying and heating drum 83 and delivers the gravel in the path of a series of intake blades 99, the front ends of which are formed with flanges bolted to the wall 98. Rearwardly of the blades 99, the drum is provided with a series of inwardly extending L-shaped blades or troughs 100 of the same number as the intake blades, and in the present instance arranged in longitudinal alignment with such blades, the trough members 100 having radial portions 101 secured by angle plates 102 to the drum wall, and terminal flange portions 103. The rear end of each intake blade extends spirally to and is secured to the leading face of the radial portion 101 of the trough member which is angularly behind it with reference to the direction of rotation of the drum, the inclined arrangement of the intake blades acting to force the material rearwardly of the drum into the spaces between the trough members. These trough members, it may here be noted, terminate a short distance forwardly of the rear end of the drying drum.

It is obvious that as the raw gravel is worked from the higher front end of the drying drum towards the rear end, the mate-

rial will be carried up by the troughs on the ascending side and fall out as it passes around the top and that the dropping of the material through the heated stream of burning gases passing through the drum will effectively and quickly dry and heat every particle of it.

The lower rear end of the drying drum is surrounded by a stationary hood or casing member 107,—see Figs. 3, 4 and 7,—the joint between the drums and casing being close fitting, or if desired, packed, to prevent escape of burning gases. Immediately beneath the rear end of the drying drum, a discharge chute 108 is removably secured to the casing 107, this chute being formed with a partition 109 separating a by-pass passage way which is normally closed by a swinging gate 110 equipped with a weight 111 for the purpose, and a lower passage which is variably opened and closed by a swinging gate 112 which yields to the weight of material pressing against it to permit passage of the material therethrough. It may here be explained that for the purpose of ascertaining the temperature of the material passing out of the drum the thermometer bulb 113 of an indicating thermometer 113^a is arranged in the by-pass, and when it is desired to make an observation the weight 111 is lifted to permit material to pass through the upper passage of the chute, and cause the temperature of the material to be indicated. Indicating thermometers of the type employed by me, as the well known Foxboro indicating thermometers are well known in the art, and need not be described in detail.

Extending through and secured to the rear wall of the hood 107 is arranged a cylindrical casing 114, lined with fire brick 115 enclosing the combustion chamber of the apparatus. The heating means employed for heating the drying drum may be a commercial oil burner of suitable type, as indicated generally by the reference number 116, having a burner tube 117 extending into the combustion chamber.

For the purpose of transferring the dried and heated gravel delivered from the discharge chute of the drying drum to the pug-mill, I employ a separable elevator including a lower frame section 118 to which is hinged an upper frame section 119, the lower section being arranged to be detachably secured near its lower end to a frame bracket 160 extending laterally from the right sill 71 of the truck frame and supported in inclined position by an inclined bracing frame or strut 120. This bracing frame is pivotally secured at its lower end to another frame bracket 161, also extending laterally from the right sill 71 of the truck frame before mentioned. When the apparatus is taken down for transportation, the brackets 160 and 161 serve as supports for the bracing frame and elevator sections.

The frame section 118 of the elevator con-

sists of a pair of opposite side bars, 118^a, secured together by a back plate 121 and overlapping front cover pieces 122; and between the bars 118^a is arranged a series of rollers 123 mounted upon pivot pins 124 secured to the bars, see Fig. 13. Each pin 124 is held in place by set screw collars 162 equipped with set screws 163. Between the two collars are interposed a pair of tubular spacing blocks 164—164 arranged on opposite sides of a roller 123 rotatably mounted in the pivot pin, and for the purpose of lubricating the bearing of the roller the pin is provided with a lubricating passage and an alemite connection. The frame section 119 is constructed similarly to the section 118. The elevator buckets 125 are secured to pairs of links pivoted to other links at intervals by means of pivot pins 126 to form a connected chain or line of buckets which ride over the rollers 123.

The frame sections are preferably provided, as shown,—see Figs. 2, 3 and 13,—with steps 200 which may be of skeleton construction, riveted to the right frame bars of the elevator sections.

At the lower end of the lower frame section, for the purpose of taking up slack in the chain, due to wear or other causes, the frame bars (see Fig. 17) are equipped with a pair of bearing blocks 167 longitudinally adjustable by means of adjusting screws 168 upon frame sections 127 secured to the bars 118^a. Between these bearing blocks is mounted an idler sprocket wheel 128 engaged by the pivots of the elevator bucket line.

The upper end of the elevator frame section 119 is detachably secured to the pug-mill frame by means of a supporting frame 168 arranged to be bolted at its top and bottom to a pair of bearing brackets 119^a secured to the side bars of said frame section and the pug-mill frame respectively,—see Figs. 1, 18 and 19. Journalized in bearings at the top of the two bearing brackets 119^a is a shaft 170 to which is fixed a sprocket wheel 129 arranged to engage the pivot pins connecting the links of the elevator bucket line. To the left end of this shaft 170 is fixed a gear wheel 136 which meshes with a gear wheel 135 fixed to the left end of a shaft 134 also journalized in bearings on the two frame brackets 119^a. The right end of this shaft 134 is arranged to be connected and disconnected by means of a clutch 171 with a sprocket wheel 133 by means of which the gearing wheels just described and elevator chain are driven (see Figs. 2, 3, and 19). To this end the right end of the shaft of the pug-mill (which is driven in the manner already described) is equipped with a sprocket wheel 131 which is engaged by a sprocket chain 132 arranged to drive the sprocket wheel 133 and connected chain of elevator buckets.

The movable member of the clutch 171 is in

the present instance arranged to be shifted by means of an operating rod 172 extending from the clutch member to the left to a convenient position for its bent end to be grasped by an operator upon the pug-mill platform, through a housing member 173 secured to the elevator frame structure and shielding the gear wheels 135 and 136,—see Fig. 3. The upper loop of the elevator bucket line is covered by a hood 130 extending from the top of the upper cover piece 122 of the elevator to the casing of a measuring device next to be described. For the purpose of observation the hood 130 is preferably provided with a door 130^a, as illustrated.

It will be noted that the elevator bucket line is completely enclosed and shielded from a point adjacent the delivery chute at the end of the heating drum to the point of delivery of the dried and heated material to the pug-mill, whereby any considerable cooling of the material is avoided.

The dried and heated gravel discharged from the elevator buckets within the hood 130 passes through a measuring device by which it is delivered in successive charges of a uniform quantity each to the pug-mill. This device includes a casing having at the top guide plates 174—175 which direct the gravel from the buckets to the center of a semi-cylindrical chamber 176 of the casing in which is arranged to work an oscillating measuring drum having parallel circular sides and three radial blades, marked 177, 178 and 179. The blade 177 is arranged to oscillate freely within the semi-circular wall of the chamber 176, but the blades 178 and 179 are of such length as to severally bring up, in extreme opposite positions of the drum, against the shoulders which the semi-circular wall of the chamber 176 makes with portions of the top wall of a rectangular discharge chamber therebelow, see Fig. 18. The shaft 180 on which the drum is mounted is counterweighted outside the casing (see Figs. 19 and 20) by a weight 181 adjustably secured upon a lever 182 fixed to said shaft, the arrangement being such that in one position of rest of the weight the blade 178 will form the floor of a compartment in the chamber between the blades 178 and 177 arranged to receive gravel from the elevator buckets, while in the opposite position the blade 179 will form the floor of a similar compartment between it and the blade 177. It is obvious that when the gravel in one compartment accumulates to a given weight it will overcome the counterbalancing effect of the weight and discharge the material through the discharge passage into the pug-mill, reversing the position of the weight and drum in doing so, and that the material will then accumulate in the other chamber with a like result, the heated gravel being thus discharged into the mill in regular measured charges. The size

of the charges may be regulated by adjustment of the weight 181 on its lever.

The rocking of the measuring drum and counterweight serves also to bring about the discharge of measured charges of heated road oil into the pug-mill through a metering device. This device (see Figs. 20 and 21) includes a cylinder 183 formed with a central partition 184, and a double piston having heads 185 and 186 which work in said cylinder on opposite sides of said head, the heads being suitably packed, and the partition being packed around the piston stem 185^a, as illustrated. In order to vary the distance between the piston heads, and consequently the maximum capacity of the chambers alternately opened on each side of the partition, one piston, as the piston 185, is mounted upon a sleeve 197 abutting against an adjusting nut 198 arranged to engage the reduced threaded end 199 of the piston stem. This rod is suitably calibrated to indicate the volume of oil discharged at each stroke of the piston, as hereinafter explained. On both sides of the partition, adjacent the partition, the cylinder is formed with ports, marked 187 and 188 which are in free communication, respectively, with branch passages 141^a and 141^b between the heated oil inlet pipe 141 and a discharge pipe 191 leading to a spray pipe 143 arranged at the top of the pug mill. Communication between the pipe 141 and either the branch passage 141^a or the branch passage 141^b is governed by a three-way valve 189, which may be ordinary construction, not illustrated, and communication between the discharge pipe 191 and either one of the branch pipes 141^a or 141^b is governed by a similar three-way valve 190 arranged to be shifted simultaneously with the valve 189. The arrangement is such that in one position of the valves the port 187 will be in communication through the valve 189 with the inlet pipe 141 while the branch passage 141^a is shut off from the discharge pipe 191 by the valve 190 and at the same time communication between the inlet pipe 141 and branch passage 141^b will be closed by the valve 189 while the port 188 will be in communication through the valve 190 with the discharge pipe 191. In the opposite position of the two valves the communications will be reversed, that is, the oil will be free to enter the opposite chamber of the cylinder through the branch pipe 141^b and port 188 and the oil which had entered through the port 187 into the other cylinder chamber is free to return and pass through the branch passage 141^a to the discharge pipe.

The valves are simultaneously oscillated to thus intermittently reverse the oil communications by means of rock arms 192 and 193 secured to the valves 189 and 190 respectively, a link 194 connecting these arms, and a sec-

ond link 195 connected to a rock arm 196 fixed to the shaft 180 before mentioned. It is obvious that a shifting of the measuring drum and counterweight from one position to the opposite will reverse the valve connections and that the piston chamber on one side of the partition which has been in communication with the inlet pipe and filled with heated oil will thereupon be placed in communication with the discharge pipe, while the opposite chamber (at the time empty) will be placed in communication with the inlet pipe, and under the pressure of an oil pump, later to be described, will fill with oil.

10 The volume of oil discharged at each stroke may be regulated by adjustment of the nut 198, before mentioned. Preferably a counting device, 205, various commercial devices suitable for the purpose being known, is employed to register the number of charges of gravel and oil delivered. This may conveniently be operated by a rod 206 connected to the rock arm 196 and the counting device.

15 The volume of oil discharged at each stroke may be regulated by adjustment of the nut 198, before mentioned. Preferably a counting device, 205, various commercial devices suitable for the purpose being known, is employed to register the number of charges of gravel and oil delivered. This may conveniently be operated by a rod 206 connected to the rock arm 196 and the counting device.

20 For the purpose of registering the total quantity of oil delivered to the pug-mill, I employ in the present instance a metering device, such as the well-known "Niagara" oil meter, 142, illustrated in outline upon Fig. 10 of the drawings, which is interposed in the inlet pipe 141 and which is provided with a dial and index hand indicating the passage of oil through the meter, and figured rollers for registering the total amount.

25 The spray pipe 143 extends over a portion only of the pug-mill, from the right end, where the dried gravel is delivered into the mill, to a point slightly over one-half the distance to the opposite or delivery end, where the mixed material is delivered to the hopper 13 beneath it,—see Fig. 3.

30 It will be understood that the capacity of the measuring drum and oil measuring device are small relatively to the total capacity of the pug-mill, so that the flow of material through the latter and through the apparatus is substantially continuous. In the machine illustrated (which is designed to deliver about thirty cubic yards of mixed material per hour) the charges of gravel and oil are designed to be delivered approximately every six seconds, and the capacity of the pug-mill and rate of travel of the material through it is such that the mill will contain approximately twenty charges at any one time. The oil flow is in fact uninterrupted except during relatively short periods of cessation of flow after the completion of each filling of one or the other of the two compartments of the cylinder in alternation, at which periods a relief valve 201 is arranged to by-pass oil from the pump, as hereinafter explained.

35 Taking up now the means for supplying road oil to the pug-mill to form the mixed material, it may first be explained that the

road oil intended to be used is of such viscosity that I contemplate a preheating of the oil to a certain degree, preferably to a temperature of from 100° to 150° Fahrenheit, by any suitable means, preliminary to supplying it to my novel mixing apparatus.

40 The oil pump of the apparatus may be of any suitable construction of suitable capacity, say 20 gallons per minute, various commercial forms of such pumps being commercially available and the particular pump employed in the present instance being a rotary pump indicated in outline in Figs. 1 and 2 of the drawings, designated as a unit by the reference number 137. The intake connection of the pump is connected with the source of supply of previously warmed road oil, preferably through a strainer 205 interposed in the inlet pipe 206, and the outlet with the pipe 138 which leads to the front end of a coil of piping 139 surrounding the front end of the drying drum within the hood 91. In a branch 200 of the pipe line 138 I have interposed the relief valve 201 above mentioned which is set to open upon a rise of pressure in the pipe 138 due to filling of one or the other of the two compartments of the cylinder 183 of the oil-measuring device hereinbefore described, the pump pressure in the line being sufficient before such rise of pressure to shift the piston of the device and fill the connected cylinder compartment.

45 The outlet or rear end of the coil 139, which in the present instance consists of eight turns, and also corresponding points on the second and fourth turns, all communicate through branch pipes 140 which may be independently opened or closed as desired by hand-operated valves with the pipe 141 leading through the oil-metering device 142 and measuring device 183 above described to the spray pipe 143,—see Figs. 2, 9 and 14. Manifestly the valves may be set to shut off either the two rear coils or the four rear coils as may be desired, to regulate the temperature of the oil in passing through the coil.

50 I have provided an indicating thermometer 144 (see Fig. 3) for indicating the temperature of the oil in the spray pipe. This thermometer may be of the same type as the thermometer 113, and has its thermometer tube 145 arranged within the spray pipe, as illustrated in dotted lines.

55 The motor, marked 146, for driving the oil pump 137, drying drum 83, and reciprocating gravel feeder 54 is mounted upon the truck frame at its rear end, see Figs. 1, 2 and 3, and is provided with clutch members for connection and disconnection with the parts driven by the engine, and the clutch shaft is connected with a speed-reducing device 147, which may be of similar construction to that of the speed reducing device 67 before mentioned. The gear wheel 147a of this device is fixed to a shaft 148 which extends longitudi-

dinally of the truck frame and is journaled in frame brackets 149 and 150. The road oil pump 137 is driven from this shaft by a sprocket chain 151 engaging sprocket wheels 5 severally secured to such shaft and the driving shaft of the pump.

The oil burner 116 which is employed to heat the drum 83 of the apparatus includes, as usual in devices of this type, a fan and a 10 pump (not shown) connected to a shaft carrying a pulley 202 engaged by a belt 203 which is driven by a pulley 204 fixed to the motor shaft.

To the front end of the shaft 148 is secured 15 a sprocket wheel 152 engaged by a sprocket chain 153 which is arranged to drive a sprocket wheel 154 fast to a shaft 155 which is journaled in bearings carried by the cross beams 73 and 74 of the truck frame,—see 20 Figs. 1, 2 and 14. The front end of this shaft is flexibly coupled with an inclined shaft section 156 to which is secured a small sprocket wheel 157 (shown in dotted lines in Figs. 1 and 14) engaged by a sprocket chain 158 meshing with a sprocket gear secured to the 25 outer face of the drying drum whereby the drum is rotated.

The front end of the shaft section 159 is equipped with a crank plate 160 which is 30 formed with a plurality of pivot pin sockets of various degrees of eccentricity,—see Fig. 8—in any one of which may be secured a pivot pin providing a pivotal connection between the crank and the lower end of a pitman rod 161 which is connected at its upper end with the horizontal arm 57 of the rocking frame by means of which the feeder plate 54 is operated. The connections at both ends of the pitman rod consist of ball and socket 35 joints, to permit the necessary movement of the connected parts. The throw of this plate and consequently the rate of feed of the raw gravel may be varied by change of the pivot pin connection of the crank plate with the 40 pitman rod.

The size and capacity of the apparatus may 45 of course vary within practical limits in accordance with the work for which it is designed to be used. In the apparatus illustrated, of capacity for general use in road making, the bins A and B may be assumed to have a capacity of about twenty cubic yards each, and the burner to have a capacity for burning from thirty to sixty gallons of fuel oil per hour. The road oil pump should 50 correspondingly have a capacity for delivering about 900 gallons of road oil per hour. The two gasoline engines may be of about twenty horse power, and all of the commercial engines and mechanisms employed are understood to be provided with the usual controls generally used in connection with such devices.

The mode of operation of the apparatus 55 will be readily understood in view of the

foregoing description, without detailed explanation. The untreated gravel, or equivalent road material, is supplied to the bin A in any convenient manner. The inlet to the road oil pump is connected to the supply tank of road oil (previously warmed to a proper degree) by a hose, not shown or any suitable connection. When the apparatus is in operation, the untreated gravel is fed by the reciprocating gravel-feeding device into the heating drum, where it is dried and heated and discharged into the bucket elevator which delivers it to the pug-mill. The road oil forced by the road oil pump through the heating coil surrounding the heating drum is delivered by the spray pipe into the pug-mill where the gravel and oil are thoroughly mixed and discharged in a heated condition into the bin B. From this bin the material is drawn out into trucks and carried to the road.

Based on a maximum moisture content of 5%, the apparatus as illustrated is designed to handle approximately thirty cubic yards of gravel per hour and assuming this degree of moisture, a proper adjustment is made of the feeding device for delivering the untreated gravel into the drying drum at that rate, and corresponding adjustments made of the road oil pump so that the proper amount of oil will be pumped through the heating coils into the pug-mill, and of the burner so that the gravel will be properly dried and heated in passing through the drying drum. The capacity of the apparatus will be proportionately greater as the moisture content is less. In the operation of the machine the two temperature-indicating devices, together with the counter indications of the number of charges of gravel and oil delivered to the pug-mill, and the adjustments provided for regulating the gravel feeding device and cutting out a portion of the heating coil, enable such adjustments of the parts of the apparatus to be made as to regulate the flow 100 of material and control the action of the drying and heating devices to produce the best results attainable, whatever variations may exist in respect to the character of materials used and the moisture content and temperature conditions.

It will be understood that in the foregoing description and in the appended claims the word "gravel" is used for convenience and brevity, and that I intend to embrace as within my invention and the scope of the claims, all equivalent comminuted solid materials which may be acted upon by the machine in the same manner as gravel. It likewise will 120 be understood that the term "road oil" is intended to embrace any and all bituminous, asphaltic or tar-like substances which possess qualities and characteristics of viscosity, etc., which permit them to be used in the same 125 130

manner as the particular material commercially termed "road oil".

I claim:

1. In apparatus of the character described and including a rotating gravel-heating drum and a stationary hood surrounding one end of said drum, and a burner arranged to discharge heated gases into and through said drum and hood, variable means for heating road oil including a heating coil surrounding said drum within said hood, a conduit having branch pipes extending from without through said hood and connected with different turns of said coil, and valves outside said hood for opening and closing communication through said branch pipes, whereby sections of said coil may be cut out from circulation.
2. In apparatus for forming a heated mixture of gravel and road oil, a supporting frame having at its top a platform and a pug-mill and a motor connected to said pug-mill mounted on said platform, a two-compartment bin structure in said frame below said platform having a raw gravel bin and having also a finished material bin below the discharge opening of said mill, a rotating drying drum having its intake end arranged adjacent the discharge opening of said raw gravel bin, means for rotating said drum, gravel feeding means intermediate the discharge opening of said raw gravel bin and the upper end of said drum, means for heating said drum, an elevator for transferring the heated gravel from the lower end of said drum to the intake end of said pug-mill, a road oil conduit including piping heated by said heating means and arranged to discharge heated oil into said pug-mill, and means for pumping the road oil through said conduit.
3. In apparatus of the character described and including a raw gravel bin having an outlet opening and a rotating drying drum having its intake end adjacent said opening, gravel-feeding means including a stationarily supported rectangular frame below said bin outlet opening having three vertical sides, a reciprocating bottom plate below the sides of the frame, and a feed chute arranged to receive gravel from said plate and direct it into said drum.
4. In apparatus of the character described and including a raw gravel bin having an outlet opening and a rotating drying drum having its intake end adjacent said opening, gravel-feeding means including a stationarily supported rectangular frame below said bin outlet opening having three vertical sides, a reciprocating bottom plate below the sides of the frame formed with vertical flanges slidably engaging the outer faces of the two opposite side walls, and a feed chute arranged to receive gravel from said plate and direct it into said drum.
5. In apparatus of the character described

and including a raw gravel bin having an outlet opening and a rotating drying drum having its intake end adjacent said opening, gravel-feeding means including a stationarily supported rectangular frame below said bin outlet opening having three vertical sides, a reciprocating bottom plate below the sides of said frame, means for reciprocating said plate including adjusting means for varying its throw, and a feed chute arranged to receive gravel from said plate and direct it into said drum.

6. Apparatus for forming a heated mixture of gravel and road oil including a rotating heating drum, means for continuously passing the gravel through said drum, a road oil conduit, means for continuously forcing road oil through said conduit means for heating the oil in said conduit, a mixing mill, conveyor means for transferring heated gravel discharged from said drum to a point adjacent said mixing mill, an automatic gravel-measuring device arranged to receive the stream of gravel delivered to it by said conveyor means and automatically deliver the same in measured charges to said mill, and means for automatically regulating the quantity of road oil passing through said conduit, said conduit being arranged to discharge into said mixing mill.

7. Apparatus for forming a heated mixture of gravel and road oil including a rotating heating drum, means for continuously passing the gravel through said drum, a road oil conduit, means for continuously forcing road oil through said conduit, means for heating the oil in said conduit, a mixing mill, conveyor means for transferring heated gravel discharged from said drum to a point adjacent said mixing mill, an automatic gravel-measuring device arranged to receive the stream of gravel delivered to it by said conveyor means and automatically deliver the same in measured charges to said mill, and an automatic oil-measuring device connected with said conduit arranged to correspondingly deliver measured charges of oil into said mixing mill.

8. Apparatus for forming a heated mixture of gravel and road oil including a rotating heating drum, means for continuously passing the gravel through said drum, a road oil conduit, means for continuously forcing road oil through said conduit, means for heating the oil in said conduit, a mixing mill, conveyor means for transferring heated gravel discharged from said drum to a point adjacent said mixing mill, an automatic gravel-measuring device arranged to receive the stream of gravel delivered to it by said conveyor means and automatically deliver the same in measured charges to said mill, and an oil-measuring device connected with said conduit and controlled by the movement of said gravel measuring device arranged to

correspondingly deliver measured charges of oil into said mixing mill.

9. In apparatus of the character described means for continuously mixing independent streams of gravel and road oil including a gravel-measuring device arranged to receive the stream of gravel and discharge the same in measured charges, an oil-measuring device having flow passages governed by the movements of said gravel-measuring device arranged to receive the stream of oil and discharge the same in measured charges, and a mixing mill arranged to receive and mix said charges of gravel and oil.

10. Mixing apparatus according to claim 9 in which said mill is of capacity to contain a plurality of charges of gravel and oil and is arranged to deliver the mixed material continuously.

11. Mixing apparatus according to claim 9 in which said gravel-measuring device includes a counter-weighted receptacle having two chambers and arranged to be reciprocated by the weight of the gravel received in the chambers alternately.

12. Mixing apparatus according to claim 9 in which said oil measuring device includes an inlet pipe and a discharge pipe, a piston and a cylinder having opposite measuring chambers and a port in each chamber, and valves operably connected to said receptacle and arranged to connect one chamber with the inlet pipe and the other with the discharge pipe, and vice versa alternately.

13. Mixing apparatus according to claim 9 in which said oil-measuring device includes a piston and cylinder having opposite measuring chambers and ports controlled by the movement of said receptacle.

14. In apparatus of the character described, a road oil conduit, a pump arranged to continuously force road oil through said conduit, a piston and a cylinder having opposite measuring chambers and a port in each chamber, a discharge pipe having branches leading to said port, valve mechanism arranged to connect one port with said conduit and the other port with said discharge pipe and vice versa alternately, a gravel-measuring device including an oscillating member, connecting means for operatively connecting said oscillating member and said valve mechanism, and means for continuously supplying gravel to said gravel-measuring device.

15. In apparatus of the character described, a road oil conduit, a pump arranged to continuously force road oil through said conduit, a piston and a cylinder having opposite measuring chambers, and a port in each chamber, oscillating valve mechanism including a rock arm arranged to shift such mechanism to opposite positions, whereby one port will be connected with said conduit and the other with said discharge pipe and vice versa alternately, a gravel-measuring

device including an oscillating receptacle and a rock shaft connected therewith, a linkage connection for operatively connecting said rock arm and rock shaft, and means for continuously supplying gravel to said measuring device.

16. In apparatus of the character described, a road oil conduit, a pump arranged to continuously force road oil through said conduit, a piston and a cylinder having opposite measuring chambers and a port in each chamber, a discharge pipe having branches leading to said port, valve mechanism arranged to connect one port with said conduit and the other port with said discharge pipe and vice versa alternately, a gravel-measuring device including an oscillating receptacle having two measuring chambers, said receptacle being arranged to be oscillated by the weight of material in the two chambers and automatically emptied and being counterweighted to stand alternately in two extreme positions until over-weighted by entering material, connecting means operatively connecting said receptacle and said valve mechanism, and means for continuously supplying gravel to said gravel-measuring device.

17. In apparatus of the character described, a road oil conduit, a pump arranged to continuously supply said conduit with oil under pressure, a relief valve in said conduit, a cylinder having two measuring chambers and a port in each chamber, a piston in said cylinder arranged to be reciprocated by oil pressure in said chambers, valve mechanism arranged to connect one port with said conduit and the other with said discharge pipe and vice versa alternately, a gravel measuring device including an oscillating receptacle, connecting means for operatively connecting said oscillating member and said valve mechanism, and means for continuously supplying gravel to said gravel-measuring device.

18. In apparatus of the character described and including a raw gravel bin having an outlet opening and a rotating drying drum having its intake end adjacent said opening, and a stationary hood surrounding said intake end of the drum, gravel feeding means including an inclined feed chute extending through said hood into said drum, said chute being provided with a swinging gate, and a feed device below said bin outlet opening arranged to feed gravel from said bin into said chute.

19. In apparatus of the character described, a combination of parts according to claim 18 in which said feeding device includes a horizontal reciprocating plate arranged adjacent said bin outlet opening.

20. Means for forming a heating mixture of gravel and road oil including a raw gravel bin provided with a feeding device at its bot-

tom, a heating drum arranged to receive gravel from said feeding device at one end and discharge the heated gravel at the other end, an elevated mixing mill, an elevator for 5 conveying heated gravel from the discharge end of said drum to said mill, an oil conduit and pumping means for forcing oil through said conduit into said mill, said mill being arranged to continuously mix said gravel and 10 oil and discharge the mixture, and a finished material bin below said mill arranged to receive material discharged therefrom.

21. Means for forming a heated mixture of gravel and road oil including a raw gravel 15 bin provided with a feeding device, a heating drum arranged to receive gravel from said feeding device at one end and discharge the heated gravel at the other end, a mixing mill, an elevator for conveying heated gravel 20 from the discharge end of said drum to said mill, means for automatically measuring the amount of gravel delivered by said elevator to said mill, an oil conduit and pumping means for forcing oil through said conduit 25 into said mill, means controlled by the movements of said gravel-measuring means for regulating the amount of oil passing into said mill, said mill being arranged to continuously mix said gravel and oil, and discharge the 30 finished mixture, and a finished material bin arranged to receive material discharged by said mill.

In testimony whereof, I have subscribed my name.
